UNITED STATES PATENT OFFICE.

EDWARD B. ROBY, OF TROY, NEW YORK, ASSIGNOR TO S. AND R. FOLDING MACHINE COMPANY, INC., OF GREEN ISLAND, NEW YORK, A CORPORATION OF NEW YORK.

MACHINE FOR FOLDING THE EDGES OF TEXTILE AND SIMILAR ARTICLES.

Application filed June 22, 1923. Serial No. 647,094.

Among the principal objects which the present invention has in view are: to adapt a machine of the character mentioned for interchanging parts for various sizes and 5 patterns of the article being manufactured; to facilitate the removal of the article in question from the machine; to so lay the material being folded as to avoid the formation of roughened or padded sections 10 in the completed article; to provide gages whereby the operation of the coordinated elements in the machine may be pre-arranged; to provide means for heating the folded edges during the period of pressure applied thereto for setting the fold; and to perfect the construction and arrangement of a machine of the character 15 mentioned for reducing the friction and wear in the parts thereof.

20 Drawings.

Figure 1 is a front elevation of the machine constructed and arranged in accordance with the present invention, the machine 25 being shown in its closed or active relation.

Figure 2 is a vertical section of the machine, the section being taken on the line 2-2 in Fig. 1.

30 Figure 2^x is a detailed view on enlarged scale showing fragments of the parts of the pressing mechanism.

Figure 3 is a top plan view of the machine and the edge turning mechanism 35 thereon.

Figure 4 is a top plan view of the bed plate of the machine showing the pressure elevator.

Figure 5 is a horizontal section of the 40 press frame, the section being taken as on the line 5-5 in Fig. 1.

Figure 6 is a detailed view on enlarged scale showing the lifting mechanism with which the pressure elevator is provided.

45 Figure 7 is a longitudinal section taken on the line 7-7 of Figure 3 of the edge turning blades and the operating mechanism connected therewith.

Figure 8 is a detailed view of the heating 50 plates with which the invention is provided.

Figure 9 is a detailed view of the edge turning members with which the machine is provided.

Figure 10 is a top plan view of parts of the mold. 55

Figure 11 is a vertical section of one of the cam shifting heads with which the folding mechanism is provided, the section being taken as on the line 11-11 in Fig. 1.

Figure 12 is a vertical section of the same mechanism, the section being taken as on the line 12-12 in Fig. 11. 60

Figure 13 is a detailed view in plan of one of the rotary cam guides with which the machine is provided. 65

Figure 14 is a vertical section of the prime mover with which the press is provided, the section being taken on the line 14-14 in Fig. 15.

Figure 15 is a horizontal section of the 70 same, the section being taken on the line 15-15 in Fig. 14.

Figure 16 is a vertical section of the valve head with which the prime mover is provided, the section being taken on the line 75 16-16 in Fig. 14.

Figure 17 is a detailed view of a portion of one of the die members constructed and arranged to upset and turn in the corner of the article being handled. 80

Figures 18, 19, 20, 21 and 22 show corner sections of the article being handled in the progressive steps of folding and pressing the edge thereof.

Figure 23 is a side view on enlarged scale 85 of the die head.

Figure 24 is a top plan view of the same.

Figure 25 is a longitudinal section of the 90 same, the section being taken as on the line 25-25 in Fig. 24. 90

Figure 26 is a cross section of the same, the section being taken as on the line 26-26 in Fig. 23.

Figures 27 and 28 are detailed views of die sections and means for holding the same 95 in service, the first mentioned figure being partly in section to show the interior construction thereof.

Figure 29 is a top plan view in detail of the die head supporting arm. 100

Figures 30, 31 and 33 are detailed views of fragments of a collar, the edge of which is turned by the herein described machine showing the construction of the inner corners of an article being constructed and the 105 method employed in constructing the same.

Figure 32 is a section of the article shown in Figure 31, the section being taken on the line 32—32 in said Figure 31.

Description.

5 In the drawings there is shown a machine embodying the present invention as adapted for folding the edges of men's collars preliminary to sewing the same, and more particularly the invention relates to improvements in the construction shown in Patent No. 1,260,060 granted me under date of March 19, 1918 for folding machines, to which patent cross reference is here made.

10 15 The style of collar to manipulate which the machine is designed has an outline corresponding to the die shown in Fig. 24 of the drawings as well as to the molds for receiving the same which is supported on the bed plate 51. The bed plate 51 is mounted in the well 52 to be elevated therein by the levers 53 at the opposite ends of the said plate. The levers 53 as can be seen best in Fig. 6 of the drawings are each provided

20 25 with a short arm 54. The long arm of the lever 53 is operatively connected by the adjusting screws 55 with the yoke 56 as shown best in Figure 1.

The yoke 56 is normally supported by a cushion spring 57 so that the levers 53 are held in their inactive position. The levers 53 are bifurcated at their ends for forming bearings for the rocking nut 58 and for the wheels 59. Intermediate the wheels 59 is disposed a leaf spring 60, the free end of which bears against the lower edge of the webbing flange with which the plate 51 is provided. While the opposite end is made fast by means of a bolt 61 to the lever 53, intermediate the ends of the spring a screw 62 is disposed in the lever 53 for the purpose of varying the tension on the spring 60.

In the inoperative relation of the plate 51 it is supported by the springs 60. When the levers 53 are rocked on their fulcrum 63, the wheels 59 engage the pendent flange of the plate 51 and thereafter positively elevate the said plate in proportion as the yoke 56 is depressed.

50 55 The yoke 56 is depressed by the operation of the piston 64 in the power cylinder 65. The operative connection between the piston 64 and the yoke 56 is formed by the piston shaft 66 and set collar 67, the latter being mounted on the rod 68 at will and by means of a set screw 69.

The power medium preferably employed in the machine herein disclosed is compressed air. This is supplied by the pipe 70 which is in communication with a suitable supply and with the valve chamber 71. The inlet port 72 and channel connected therewith introduces the compressed air above the piston 64, while the port 73 admits the air below the said piston, the passage 74

communicating between said port and the valve chamber 71. The exhaust pipe 75 is connected with the port 76 which is exposed by the valve 77 at the extremes of travel of the said valve and by means of the passage 78, usual to the construction of reciprocating slide valves. This construction can be best seen in Figures 14 and 15 of the drawings.

As can be best seen in Fig. 2 of the drawings, a dash pot 79 having a perforated piston 80 mounted therein controls or quiets the operation of the piston 64 and parts connected therewith. The piston shaft 66 has connected therewith the piston rod 68 to which is permanently attached the piston 80, a gland packing 81 preventing the leak therefrom of a suitable liquid with which the dash pot 79 is provided.

As can be best seen in Fig. 2 of the drawings when disposed inactively the yoke 56 and the portion thereof through which the rod 68 extends is spaced apart from the collar 67 to provide a predetermined amount of lost motion in the operation of the machine prior to the actual rocking of the levers 53. During this period, or in correspondence with the lost motion, the levers 82 and 83 are rocked on their pivots 84 and in the order named.

As will be seen by reference to said Fig. 2, the opposite sides of the shaft 66 adjacent the cylinder 65 and where the same extends through the lower head thereof, the said shaft has a relatively short recess 85 and a relatively long recess 86. In the short recess 85 a head 87 on the lever 82 rests while in the long recess 86 a similar head 87 belonging to the lever 83 deposes. The result of this construction is that immediately the piston 64 and the shaft 66 begin their downward movement, the lever 82 is rocked on its pivot 84, the head 87 being forced out of the recess 85. This effect is consummated and the free end of the lever 82 which is operatively connected by a link arm 88 is elevated to its full movement before the head 87 of the lever 83 is similarly forced from its recess 86 to be rocked so that the free end thereof and the link arm 88 with which it is connected in turn elevated.

It is subsequent to the complete elevation of the link arms 88 and parts associated therewith that the collar 67 engages the yoke 56 which is thereafter depressed by the continued movement of the piston 64 and parts associated therewith.

As explained, the rocking of the levers 53 operate to primarily compress the springs 60 and thereafter by the wheels 59 force the bed plate 51 upward with full force to compress the edge of the collar being treated, the edge of which has in the meantime been folded.

By observation of Fig. 2 of the drawings

it will be seen that the link arms 88 are each provided with a hollow open ended tubular head 89. The heads 89 as will be seen in Fig. 2 of the drawings have a squared rear extension 90 guided by the flanges 91 of the bracket plate 92. Movable mounted in each of the heads 89 are ends of levers 93, the opposite ends of which are bifurcated to form yokes having disk ends 94 fitting into the grooves 10 in the nuts 95 which are slidably mounted on the rods 96 as best seen in Figures 1, 11 and 12 of the drawings. The rods 96 have screw-threaded sections at the lower ends whereon are mounted the nut and lock-nut 97 and 98, respectively. The disposition of the nut 97 regulates the amount of lost motion provided for the levers 93 when rocked by the link arms 88 and levers 82 and 83 respectively.

From the foregoing it will be seen that as each of the link arms 88 and the heads 89 connected therewith are elevated, the nuts 95 are depressed until they engage the nuts 97. Thereafter the nuts 97 and parts connected therewith are depressed to the end that the sliding heads 99 and parts associated therewith are moved in accordance with the direction to which the cam arms 100 are turned.

As is seen best in Figures 11 and 12, the arms 100 are rigidly connected with shafts 101 which are reciprocatively mounted in rotary tubular extensions 102 of the slide plates 103. The plates 103, as best seen in Fig. 13 of the drawings, have bolting flanges 104 to receive the guard rails 105, which hold the heads 99 on the plates 103. In Fig. 13 of the drawings may also be seen the bore 106 provided for the shaft 101 and an offset recess 107 to receive the arms 100 when depressed at the working position as shown in Fig. 11 of the drawings.

It will be noted by reference to Figures 1 and 2 of the drawings that the levers 93 are disposed in pairs, each pair operating simultaneously to elevate or depress the arms 100 connected therewith. It will also be understood from the foregoing description and as seen best in Fig. 2 that the pair of levers 93 and the link arms 88 connected therewith at the back of the machine are operated in advance of the levers 93 at the front of the machine. This precession of the operation at the rear of the machine results in folding the edge of the collar turned toward the rear of the machine in advance of a similar operation on the edge of the collar turned toward the front of the machine.

The collar above referred to is blanked or cut from a suitable material and in accordance with the pattern the dimensions whereof are sufficiently greater than the die shown in Fig. 24 of the drawings, to permit folding the edge over the said die to form a hem 65 for the collar which may subsequently be

stitched down after being pressed. The die shown in Fig. 24 is preferably formed by end sections 108 and a middle section 109. Said sections are operatively connected with spindles 110 as best seen in Figures 26 and 28 of the drawings, the said spindles being each provided with locking nicks 111 for engagement by the springs 112 as can be best seen in Fig. 24 of the drawings. The spindles 110 are provided with foot plates 75 113 to which the said sections 108 and 109 are removably attached by means of clips 114. By this arrangement of the sections 108 and 109 a variety of shapes may be employed, in connection with the present machine.

The springs 112 are mounted on small blocks 115, the ends of the said springs resting in edge opening slots 116 in the ends of said blocks. The slots 116 extend through the walls of bores 117 in the blocks provided to receive the spindles 110. In the working position of the spindles 110 and the blocks 115 the nicks 111 register with the slots 116 so that the ends of the springs 112 rest within the nicks 111 thereafter forming an efficient lock to prevent the withdrawal of the said spindles from the blocks 115. The center block 115 connected to the middle die section 109 is rigidly secured to a channel bar 118 by means of a screw 118', as best shown in Figures 25 and 26 of the drawings. The end blocks 115 connected to the end die sections 108, are mounted on the channel bar 118 for longitudinal movement relative thereto, and the means for this end as well as the purpose thereof will be pointed out hereinafter. The channel bar 118 is rigidly mounted upon and at the end of the retaining arm 119. The arm 119 as best seen in Figures 2 and 29 is preferably mounted on the shaft 120; the bearings whereof are formed in brackets 121. The arm 119 is held in operative position primarily by the arm 122 and the compression spring 123 which rests between the arms 119 and 122. The arm 122 is pivoted on the shaft 120 and has a rearward extension at the end whereof is a foot plate 124.

The foot plate 124 as is shown best in Fig. 2 of the drawings is interposed in the path of the roller 125 mounted at the end of the arm 82 which as previously stated is raised by the movement of the piston 64 and in advance of the arm 83. The shaft 120 to which the arm 119 is rigidly secured is rigidly attached to an arm 126 to which the operating rod 127 is connected that is attached to the foot operated lever 128. The lever 128 is pivoted at 129 and is provided with a foot treadle 130 which construction can be best seen in Fig. 2 of the drawings. To the arm 126 is attached a pull spring 131, which normally depresses the free end of the arm 126 and the free end of the lever 130.

128. In this position the shaft 120 is rocked to dispose the arm 119 and parts associated therewith including the die sections 108 and 109, in the raised position leaving the molds 5 opening on the bed plate 51 free for the introduction of the cloth blanks from which the collars are constructed.

From the foregoing it will be seen that when the operator places his foot on the 10 treadle 130 to depress the same, he rocks the shaft 120 and the retaining arm 119 into position where the die sections 108 and 109 press the cloth into the mold to rest on the bed plate 51. At the same time the back 15 of the arm 126 impinges upon the set screw 132 on the arm 122 which rocks the said arm 122 to the position shown in Fig. 2 of the drawings. If now power be applied to move the piston 64 it will be seen that the 20 first result of the movement of the said piston 64 will be to introduce the end of the arm 82 and the roller 125 carried thereby in the path of and in engagement with the foot 124 of the arm 122. From this it is obvious 25 that thereafter the die head at the end of the arm 119 is held firmly against the subsequent pressure imparted by the bed plate 51 when the same is elevated by reason of the engagement of the nut 67 with the yoke 30 56. It will further be observed that in accordance with the tension of the spring 123, the pressure is maintained on the arm 119 and the die sections 108 and 109 carried thereby.

35 The valve 77 is moved by the rod 133 which is connected by means of a pin and slotted end to the lever 128. The slot provides for lost motion in the lifting of the rod 133 sufficient to rock the arm 119 to retaining position. Thereafter the lift of the 40 rod 133 moves the valve 77 to expose the port 72 with the result that compressed air is delivered above the piston 64 which thereafter is depressed as rapidly as the dash 45 pot 79 and parts associated therewith will permit, resulting successfully in the folding of the edges of the cloth held by the die sections 108 and 109 over the said dies and subsequently applying pressure thereto from beneath by elevating the bed plate 51.

50 The folding of the edges is accomplished by first upstanding the material around the die sections 108 and 109 as the material is forced upon the bed plate 51 by the operation 55 of the retaining arm 119, the channel bar 118 and the die sections above mentioned. In this operation the material is forced downward through the mold formed by the heating plates 134 and the folding sections 135, 136 and 137 to rest on the bed plate 51 in the mold formed by the mold plate 138. After the raw edge of the material is placed thus upstanding, it is folded over the die sections 108 and 109, the folding sections 135, 136 and 137 being shifted 60 65

toward the center of the die for this purpose.

The folding sections 135, 136 and 137 rest snugly on the overturned material above the die sections 108 and 109. The sections 70 135, 136 and 137 are thus moved in correspondence with the movement of the cam arms 100 and the sliding heads 99 operatively connected therewith. To this end the plates 135, 136 and 137 are provided 75 with upstanding stud posts 139 and 140. As shown best in Fig. 3 of the drawings the posts 139 protrude through the openings 141 in the heating plates 134. The stud posts 139 and 140 are operatively connected with 80 shifting bars 142 which are rigidly connected to the brackets 143. The brackets 143 as best shown in Figures 11 and 12 are provided with collars 144 pivotally connected with the circular turret 145 on the 85 sliding heads 99. The posts 140 are fixedly attached to the ends of the bars 142, to move in correspondence therewith. The bars 142 are maintained in parallel relation to the swing bars 146 and to the work being 90 performed, by links 147 which as shown best in Fig. 3 of the drawings, are pivotally attached to the bars 142 and 146 and are of equal length.

95 From the foregoing it will be observed that when the sliding heads 99 are moved, the cam arms 100 shift the brackets 143 toward the center of the machine in correspondence with the angles of inclination 100 of the said cam arms 100, the bars 142 being rigidly attached to the brackets 143 by the bolts 148. The said bars 142 are moved in correspondence with the shift of the sliding heads 99. The connecting bars 146 105 maintain the alinements of the bars 142 during the movements thereof.

110 The angle of movement of the sliding heads 99 or the operating angles of the cam arms 100 may be varied by rotating the plates 103 about the center of the tubular extensions 102. Set screws 149 best shown in Fig. 11 of the drawings may be employed for locking the extensions 102 in adjusted position. To assist in the adjustment the plates 103 have pointers 150 which extend 115 over and register with the calibrations 151 provided on the bosses 152 of the bed plate of the machine.

120 The plates 134 are supplied with electrical heating elements 153. The heating elements 153 are constructed in accordance with any approved design and are preferably placed in the plates 134 adjacent the edge of their central opening which corresponds to the shape of the assembled die sections 108 and 109 and to the opening in the mold plates 138 to which the said heating plates 134 are rigidly attached by the stud screws 154 shown best in Fig. 10 of the drawings, the 125 said heating plates having perforations 155 130

through which the said stud bolts extend when the parts in the machine are assembled. It will be understood that the heating plates 134 are removably attached to the present 5 machine and adjustably held thereon by bolts 156. The heating elements are supplied by electrical current, the current wiring of said elements being connected to the plug terminals 157 to which in service socket terminals are applied, which are connected with a source of electrical supply.

From the foregoing it will now be seen that when operating the machine, the attendant places a cut blank over the mold 15 opening in the plates 134, 135, 136, and 137 and plates 138, the edges of the blank overlying the opening in the plates 135, 136, 137 and 138. The blank having been placed, the treadle 130 is depressed so that the lever 20 128 is rocked on its pivot 129. Before the rod 133 is engaged, the rod 127 is lifted to depress the retaining head 119 to its working position in arriving at which, the die sections 108 and 109 engage the blank 25 and force the same into the mold opening of the plates 138 and between the inner edges of the folding sections 135, 136 and 137.

The above is the position assumed by the 30 parts which upturns the edges of the blank in the mold. When the lever 128 engages the rod 133, the rod 133 is lifted by the continued movement of the lever 128 with the result that the rod 133 shifts the valve 35 77 upward to expose the passage 72 to the compressed air coming through the pipe 70. This compressed air entering above the piston 64 depresses the same with the shaft 66 with which it is connected. The shaft 40 66 in its operation rocks the levers 82, 83 in the manner above described, with the result that pairs of levers 93 at the back of the machine and at the front of the machine are rocked successively in the order named. The 45 outer or disk ends 94 thereof being depressed. The nuts 95 engaging the nuts 97 on the rods 96 depress the cam arms 100 with the result that the sliding heads 99 and brackets 143 are moved toward the center of the 50 machine in correspondence with the angle at which the slide plates 103 and the cam arms 100 are set.

As above described the movement of the brackets 143 toward the center of the machine operating through the bars 142 and 146 shift the folding sections 135, 136 and 137 toward the center of the mold and over the adjacent edges of the die sections 108 and 109 folding the material of the blank 60 which was upstanding to lay it down close upon the said die sections.

It will be noted that the precession of the movement of the levers 93 at the back of the machine in relation to the levers in front of the machine results in laying the

upstanding edge of the blank upon the die sections at the back of the machine before the rest of the material is laid.

The above actions resulting in the over-laying of the edge of the machine is completed and the folding sections 135, 136 and 137 are brought to rest before the shaft 66, and the rod 68 connected therewith engages the yoke 56. When the engagement does take place, the levers 53 are rocked to lift the bed plate 51 with force, pressing the material of the blank and the overturned edges thereof upward against the sections 135, 136 and 137. This pressure is exerted until the operator releasing the treadle 130 permits the spring 131 to pull the rod 127 downward rocking the lever 128 to depress the rod 133 and shift the valve 77 so that the passage 78 opens communication between the inlet port 72 and the exhaust port 76, and open the port 74 to admit compressed air to enter the piston 64 which is then returned rapidly to its lifted position reversing the various operations above described, resulting in relieving the pressure on the bed 90 plate 51, retracting the folding sections 135, 136 and 137, and lifting the retaining head 119 and the die sections 108 and 109 carried thereby together with the blank, the edges of which have been overturned and compressed. The blank is thus presented to the operator in condition to be easily removed.

While the folded edge is under pressure it will be understood that it is directly heated by the heating pad 158 on the bed plate 51 and by the heating elements, and indirectly heated by the elements 153 in the plates 134. The heating of the elements 153 is transferred to the sections 135, 136 and 137, which being heated, operate upon the over-folded edge. By this arrangement, however, if for any reason the machine is arrested in its operation with the pressure applied to the folded collar edge, the heat in the sections 135, 136 and 137 is gradually 110 diminished by absorption to the collar and is augmented by the time during which the pressure is maintained. The binding terminals 159 as seen best in Fig. 6 of the drawings supply electric current to an electric heating element of conventional type contained in the pad 158.

It now remains for the operator to remove the collar from the die sections 108 and 109. This is accomplished by moving the end 120 blocks 115 which support the die sections 108 toward the die section 109. The spaces between the die sections 108 and 109 shown best in Fig. 24 of the drawings is sufficient 125 to provide enough movement of the die sections 108 to clear the same from engagement with the overturned edges of the said blanks. When thus cleared it is obvious that the blanks may be quickly and easily removed from the said die sections. To the end that 130

the blocks 115 may be shifted, they are slidably mounted in supporting blocks 160. The blocks 160 as best shown in Fig. 25 of the drawings are fixedly mounted on a channel 5 bar 118 by means of screw bolts 161. The block 160 has extensions 162 and 163 which are adapted to rest in the recesses 164 and 165. The extension 162 normally engages the block 115 for maintaining the service 10 relation thereof. The extension 163 extends into the recess 165 only when the block 115 is moved backward against the pin 166 to compress the spring 167 behind the said pin.

15 Engaging the outer end of the pin 166 is a spring 168 which is anchored at the lower end to the block 115 and which normally supports the said block in service relation to the channel bar 118 and to the block 160.

20 When it is desired to remove the compressed collar or blank from the die sections 108 and 109, the end blocks 115 are moved toward the center block 115, or referring to Fig. 27 of the drawings the block 115 shown there- 25 in would be moved to the right until the die 108 connected with this block 115 is drawn from under the overturned edge of the blank.

It will be noted by reference to Fig. 27 30 that the inner ends of the recesses 164 and 165 are flared or widened. This permits the block 115 to be rocked on the center of the block 160 without disturbing the said block.

The rocking action thus imparted to the 35 die 108 with which the block 115 is connected disposes the blank in position to be readily removed from the said die. When the block 115 is thus rocked the spring 168 extending from the pin 166 is stretched.

40 When the block 115 is released the spring 168 returns the block to its normal position.

In Figures 30 to 33 inclusive are shown modified forms of collar blanks. These 45 blanks have the material thereof adjacent the inner angle of the blank embossed to form raised sections 169 at the outer edges of the material constituting the blanks. When this material is thus subsequently overturned as shown in Fig. 33 of the drawings, it will be found that the material has 50 been stretched by embossing the same so that it extends around the inner angle formed by the overturned edge without crinkling or ridging.

55 In Figures 18 to 22 of the drawings there is illustrated, step by step, the method of turning the outer angles or corners of the blanks and to perfect the joint indicated in Fig. 22 by the numeral 170. The successive steps are shown as in Figure 19 where the pointed extremity 171 is upturned, in Fig. 20 where the said pointed end 171 is folded over, in Fig. 21 where the sides of the pointed ends 171 and the edge 172 of the blank 173 together with the sides of the

said end 171 have been upturned, and finally in Fig. 22 where the edge 172 folded upon the blank 173 as well as the sides of the extremity 171.

The outer or pointed corners of the collar 70 are formed as above described by means of the block 174 and the side pieces 175 and 176 shown best in Fig. 17 of the drawings.

The side pieces 175 and 176 and the blocks 75 174 are permanently mounted upon the fold- 17 ing sections 136 as shown best in Fig. 9 of the drawings.

When the sections 135 and 136 are thus equipped the material constituting the blank is first acted upon by the blocks 174. 80 The blocks 174 upturn the pointed extremities 171. In the position shown in Fig. 19 of the drawings the continued downward movement of the die sections carries the blank between the side pieces 175 and 176 85 imparting to the material adjacent the extremities 171, the fold indicated in Fig. 21 of the drawings. From this point the continued movement of the die sections 108 and 109 carries the material down between the 90 mold plates 138 to receive the folding sec- 95 tions 135, 136 and 137 as the same are im- mediately moved in over the upstanding edge and which complete the edge and the fold at the pointed extremity of the blank 95 as shown in Fig. 22 of the drawings.

Having thus fully described the invention, what is claimed, is:—

1. In a folding machine of the character described, a table having a well therein, a bed plate in the said well, mould plates resting on said table and overlapping the said well and having cutouts corresponding to the contour of the end portions of the article to be formed, said mould plates being 100 movable towards and from each other to determine the length of the article when formed, a die disposed above said bed plate, means for carrying said die and moving the same towards and away from said bed plate, means for turning the edge portions of a blank over said die when the blank is clamped between the die and the bed plate, and means for imparting movement to said 105 turning means.

2. The structure of claim 1 wherein the turning means embodies intermediate plate sections and end plate sections, the end plate sections being movable towards the intermediate plate sections, and means carried 110 by the end sections for turning the corner portions of a blank upwardly for the folding of the same downwardly and under the main portion of the blank when the intermediate plates are moved inwardly toward each other to fold the edge portions of the blank upon the die.

3. In a folding machine of the character described, a table having a well therein, a bed plate in the said well, an arm pivoted 120

to said table, a die carried by said arm and disposed above said well, a lever pivoted to said table and having one end engageable with said arm, a treadle bar, a link connecting said treadle bar to said lever for imparting movement to the same and to depress said arm and die, a mold upon said table and overlapping the said well and having a die receiving opening conforming to the contour of said die, and seam turning plates slidable above the mold for engaging edge portions of a blank clamped between said die and said bed plate and turning the edge portions of the blank down upon the die substantially as and for the purpose set forth.

4. In a folding machine of the character described, a table having a well, a bed plate in the said well, a die disposed over the said well, means for supporting said die for movement towards and away from said bed plate, means for imparting movement to said die supporting means, turning plates slid-

able horizontally for engaging edge portions of a blank and folding the same over onto said die to form a seam portion, inclined arms slidable vertically, sliding heads receiving said arms and having track forming heads, blocks slidable horizontally in said heads, the arms embodying inclined cam pins extending through inclined openings in said blocks to impart sliding movement to the blocks when the arms are moved vertically, bars connected with said blocks and having longitudinally extending slots therein, heating plates disposed above said turning plates and having inclined slots therein, stems extending from said turning plates through the slots of said bars and heating plates, and means for moving said arms vertically to impart horizontal movement to the said blocks and bars and through the medium of said stems to impart sliding movement to said turning plates.

EDWARD B. ROBY.
